UNITED STATES PATENT OFFICE.

JEROME HIRSHFELD, OF NEW YORK, N. Y.

SUGAR-CONTAINER.

1,140,822.

Specification of Letters Patent. Patented May 25, 1915.

Application filed August 24, 1914. Serial No. 858,226.

To all whom it may concern:

Be it known that I, JEROME HIRSHFELD, a citizen of the United States, and a resident of the city of New York, borough of Manhattan, in the county and State of New York, have invented a new and Improved Sugar-Container, of which the following is a full, clear, and exact description.

This invention relates to kitchen and table articles, and has particular reference to containers for lump sugar or the like, the individual lumps or packages of which are to be dispensed or withdrawn singly.

Among the objects of the invention is to provide a container of the character indicated, which is of a neat appearance, sanitary in use, and easy of manipulation.

The foregoing and other objects of the invention are carried out by a mechanism substantially as hereinafter more fully described and claimed, and illustrated in the accompanying drawings, in which—

Figures 1 and 2 are perspective views of the base and top portions, respectively; Fig. 3 is a vertical section on the line 3—3 in Fig. 4; and Fig. 4 is a transverse section on the line 4—4 of Fig. 3.

The several parts of the device may be made of any suitable materials, and the relative sizes and proportions thereof, as well as the general design of the mechanism, may be varied to a considerable extent without departing from the spirit of the invention hereinafter claimed.

Referring more particularly to the drawings, I show in Fig. 1 a main portion of the container, comprising a base 10 and a pedestal 11. These parts are preferably molded or cast as an integral structure, as from glass or some other suitable, cheap, sanitary material.

The pedestal portion is shown tapered somewhat toward the top, and comprises a plurality of substantially upright receptacles or chambers 12, shown in this instance as three in number, but it will be understood that a greater or less number may be employed. Each of these chambers 12 is formed by parallel side flanges 13, spaced according to the length of the blocks or packages to be held therein and dispensed therefrom. By way of illustration, the commodity to be dispensed may be understood to be lumps of sugar S, a column of which is contained in each chamber 12. The lowermost lump of the column is supported upon

a pair of flanges 14, lying in a substantially horizontal plane at the lower ends of the flanges 13, and extending toward, but spaced from each other, the space being indicated 60 at 15 and being wide enough for the easy insertion of one's finger between the flanges 14.

The rear wall 16 of each chamber 12 is recessed or undercut, as shown at 17, whereby the end of the finger may easily be slipped upwardly in the rear of the lowermost lump S. The groove 17 may extend upwardly along the rear wall 16 to any desired point, but shown in the illustrations 70 as being co-extensive with the chamber 12, thereby adding to the beauty of the device and saving in material. This groove 17, furthermore, when extended all the way up to the top of the pedestal, facilitates the re-charging of the device with the commodity 75 to be dispensed.

As indicated in Fig. 3, the upward taper of the pedestal insures that the top of each column of lumps is inclined inwardly toward the vertical axis of the pedestal, and hence there is little likelihood that any column will topple over outwardly when the cover is not in place.

The cover, as indicated at 18, is of a 85 shape to fit loosely upon the pedestal 12 when filled with the commodity to be dispensed, and rests at its bottom edge upon a flange 19, which surrounds the bottom of the pedestal, broken only by the lower ends 90 of the chambers or spaces 12. The drawings indicate that the depth of the chambers 12, from the front toward the center, is substantially equal to the width of the lumps of sugar, and hence the cover 18 is provided 95 with as many flat faces 20 as there are channels or chambers 12, adjacent to which the faces come when the cover is in place. In other words, the other edges of the lumps of sugar or other commodity are loosely 100 fitted just in the rear of the inner surfaces 20; that is to say, the lumps or packages are of a size and form to fit loosely in the chambers 12, but adapted to slide downwardly therealong as the bottom packages or lumps 105 are removed.

The flanges 14 which support each column of lumps are arranged far enough below the horizontal plane of the flange 19 to allow the lowermost lump to be withdrawn outwardly freely, as will be seen in Fig. 3. The next upper lump, however, will be restrained

- by the lower edge of the face 20 of the cover. Hence, all of the column will be retained in the chamber except the single lump at the bottom, with which the operator's thumb and finger may be engaged. It is obvious also that the lump to be removed may be grasped by a pair of tongs or other device, if it is not desired to grasp it with the fingers.
- 10 The top of the cover is closed but for a central hole 21 passing downwardly over and around a shank 22 formed at the top of the pedestal. The extreme upper end of the shank is preferably screw-threaded at 23 for coöperation with a retaining device in the nature of a main cap and finger-piece 24, which coöperates directly with the threaded part 23, and has a flange 25 which bears upon the upper surfaces 26 of the cover top, serving to hold the cover in place. The cap 24 may be ornamented in any suitable way, and serves as a convenient means of lifting the device as a whole, when desired.

When the cover 18 is made of glass, it is 25 obvious that the condition of the chambers 12 may readily be observed through the flat portions 20 thereof. When the container needs to be refilled, the cap 24 is unscrewed, and the cover removed and set aside, leaving the chambers exposed for filling with lumps of sugar or the like. When these chambers are filled, the lumps remain in place, due to the inclination of the rear wall 16 of each chamber, and then the cover is 30 placed and secured as above described.

Having thus described my invention, I claim as new and desire to secure by Letters Patent:—

1. A container comprising a base, a pedestal thereon formed with a plurality of spaced chambers, the rear wall of each of which is inclined toward the top of the pedestal and adjacent its lower end is provided with a recessed portion, a pair of 40 spaced flanges extending from the said pedestal into the lower end of each of the said chambers, the opening between the spaced flanges in each chamber making communication with the said recessed portion of its rear wall, a cover fitting over the said pedestal, and a rib on the outer lower portion of the 45 said pedestal and extending between the

said chambers therein to support the said cover with the lower edge thereof a predetermined distance above the said pairs of 55 spaced flanges.

2. A container comprising a base, a pedestal thereon formed with a plurality of spaced chambers in the rear wall of each of which adjacent its lower end is a recessed portion, a pair of spaced flanges extending from the said pedestal into the lower end of each of the said chambers, the opening between the spaced flanges in each chamber making communication with the said recessed portion of its rear wall, a cover fitting over the said pedestal, a rib on the outer lower portion of the said pedestal and extending between the said chambers therein to support the said cover with the lower edge 60 thereof a predetermined distance above the said pairs of spaced flanges, and means for securing the said cover in position.

3. A container comprising a base, a pedestal thereon formed with a plurality of 75 chambers, the rear wall of each of which is inclined toward the top of the pedestal and is provided with a recessed portion adjacent its lower end, spaced flanges extending from the pedestal into the lower end of each chamber with a space between the flanges in each chamber extending into the said recessed portion of its rear wall, the said pedestal being also recessed in those portions thereof extending between the said chambers, a 80 cover adapted to fit over the pedestal and provided interiorly with alternating straight and convex sides, the former adapted to extend over the said chambers and are inclined at the same angle as the rear walls thereof 85 and the latter to fit within the recessed portions of the pedestal extending between the chambers, and means for securing the said cover in position with its lower edge a predetermined distance above the said spaced 90 flanges.

In testimony whereof I have signed my name to this specification in the presence of two subscribing witnesses.
